CLAIM

The ornamental design for a landscaping brick, as shown and described.

DESCRIPTION

FIG. 1 is a perspective view of a landscaping brick of the invention;

FIG. 2 is a top view of the brick shown in FIG. 1;
FIG. 3 is a front view of the brick shown in FIG. 1;
FIG. 4 is a left side view of the brick shown in FIG. 1;
FIG. 5 is a right side view of the brick shown in FIG. 1;

FIG. 6 is a rear view of the brick shown in FIG. 1; and,
FIG. 7 is a bottom view of the brick shown in FIG. 1.

FIG. 1

FIG. 2

FIG. 4

FIG. 3

FIG. 5

FIG. 6

FIG. 7
